DESIGN FOR A BACK FOR BILLFOLD OR SIMILAR ARTICLE

Arthur A. Tolbert, Yoakum, Tex., assignor to Texas Tanning & Manufacturing Co., Yoakum,
Tex.

Application February 15, 1944, Serial No. 112,592

Term of patent 3½ years

(Cl. D87—3)

To all whom it may concern:

Be it known that I, Arthur A. Tolbert, a citizen of the United States, residing at Yoakum, in the county of Lavaca, State of Texas, have invented a new, original, and ornamental Design for a Back for Billfold or Similar Article, of which the following is a specification, reference being had to the accompanying drawing, forming part thereof.

Figure 1 is a top plan view of a back for billfold or similar article showing my design;

I claim:

The ornamental design for a back for billfold or similar article, as shown and described.

ARTHUR A. TOLBERT.
